UNITED STATES PATENT OFFICE.

CLAYTON W. OLD, OF MONTCLAIR, NEW JERSEY, ASSIGNOR TO SHUR LOC ELEVATOR SAFETY COMPANY, INC., OF NEW YORK, N. Y., A CORPORATION OF NEW YORK.

ELEVATOR.

Application filed April 29, 1925. Serial No. 26,571.

In an application of Glenn S. Williamson, Serial No. 568,396, filed June 15, 1922, there is shown and described a mechanism for the operation of the shaft doors of an elevator in which a normally retracted device on the car is adapted to be moved into extended operative position with respect to the door to be moved and is then moved bodily to move the door. The movement of the normally retracted device to extended position is effected by the movement of the controller lever of the car and in order to guard against the opening of the door when the controlling lever is not in its neutral position, and the car is therefore capable of movement, there is provided a mechanical interconnection between the controlling lever and the moving means such that the retracted device cannot be moved to extended position while the controlling lever is out of normal position. Under some conditions of use of the elevator it may be desirable to prevent the movement of the car whenever the door operating device is moved from its normally retracted position, regardless of the position of the controlling lever of the car. It is the purpose of this invention to provide means whereby this result can be accomplished and in accordance therewith the movement of the door operating device from its normally retracted position is made to effect interruption of the car operating means whatever may be the position of the controlling lever of the car. In the preferred embodiment of the invention the movement of the door operating device from its normally retracted position is made to open a switch so placed in the electrical connections through which the movement of the car is controlled, as to prevent the application of power to move the car. The invention will be more fully explained hereinafter with reference to the accompanying drawings in which it is illustrated and in which—

Figure 1 is a view in front elevation, partly broken away, showing a portion of an elevator car and of a shaft door and the devices for effecting and controlling the movement of the shaft door.

Figure 2 is a view in elevation as seen from the right hand in Figure 1, with some of the electrical connections indicated schematically.

Figure 3 is a detail view of some of the

parts shown in Figure 1, other parts being omitted for the sake of clearness.

Figure 4 is a schematic view indicating some of the electrical connections.

Figure 5 is a schematic view illustrating a suitable arrangement of devices for effecting and controlling the movement of the elevator car.

In the drawings there is shown at *a* a portion of the frame or body of an elevator car of ordinary construction, the floor being indicated at *a'*. As indicated schematically in Figure 5 the car may be raised and lowered through the medium of a cable *x* which passes over suitable guides *x'*, *x''* and *x'''* secured to a drum *x⁴* operated by a motor *x⁴* which receives current through a controller box *x⁵* which is electrically connected as by a cable *x⁶*, with control devices mounted on the car and including a controller box *x³* with a handle *x⁴*, a cut-out switch *x⁵*, to be operated by hand when necessary, and a second cut-out switch *x⁶* to be operated in the movement of the door operating device hereinafter referred to. It will be understood that the electrical devices through which movement of the car is controlled may be constructed and arranged as may be preferred, the present invention not being concerned with the particular construction and arrangement thereof.

At each floor or shaft landing there is a suitable door *b* which is movable horizontally to open or to close the shaft opening and is conveniently shown here as a collapsible gate, although in practice it is usually a sliding door. The door operating devices may also be constructed and arranged as preferred, except as hereinafter indicated, and for convenience they are illustrated as in the application of Elwood S. Brinker and John R. Haviland, No. 19,255, filed March 30, 1925. As therein shown, the power devices are actuated by compressed air from a tank *e* on the car, the air being conducted to the power devices through a pipe *e'* which is connected to a four-way valve *e³* under the control of the operator for the purpose of enabling him to direct the delivery of air through one or the other of two branch pipes *e⁴*, *e⁵*, to one or the other of two power cylinders *f*, *f'* mounted on the car, the one exhausting as the other is charged with air under pressure to move the door in the desired direction. The pistons of the two

cylinders are connected by a rack bar indicated at f^4 in Figure 2 which engages a gear g^2 from which, through chains g^3 , g^7 and sprocket wheels g^5 , g^6 motion is imparted to a traveler h which is mounted to travel to and fro across the top of the car on rails h' .

The traveler h is adapted to be operatively connected with the door to be moved by a device or member which normally is retracted so that in the movement of the car it will not collide with any portion of the shaftway, and is capable of being moved to extended position or into operative relation with the door to be moved. In the construction illustrated the door engaging device or member consists of two shoes h^2 hung so as to swing upon vertical axes from the retracted or inoperative position, the two shoes being spaced apart, when in operative position, so as to receive between them the coating device or devices on the shaft door, as shown at b' . Arms h^3 on the shoes h^2 are provided with rollers h^4 adapted for contact with a bar i which is hung by pivoted arms i' from the supporting framework on top of the car and is adapted to be swung from its normal, inoperative position, to its operative position to bear against the rollers h^4 to cause the shoes h^2 to swing from their normal, inoperative position, to their operative position, against the pressure of springs, not shown, which hold the shoes normally in their inoperative position. As the bar or rod i extends across the top of the car throughout the length of travel of the traveler h it will, while in its operative position, hold the shoes h^2 in their operative position throughout the movement of the traveler.

In the normal operation of the elevator, the bar i is moved to operative position at the initial movement of the rack bar f^4 , before that rack bar engages the gear g , by devices such as those described in said application Serial No. 19,255, but need not be described herein since the present invention is not concerned therewith. Under some conditions of operation the bar i may be moved by other means, such as those described in said application and likewise not necessary to be explained herein. So far as the present invention is concerned, it is only necessary that there shall be on the car a normally retracted device, such as the shoes h^2 , for example, adapted to be moved by some means into extended operative position with respect to the door, provision being made, in accordance with the present invention, whereby the movement of such a device, which is preliminary to the movement of a door, shall prevent movement of the car independently of the controller handle a^4 and without regard to its position.

To effect the present purpose there is included in some part of the electrical devices through which the movement of the car is

controlled, as in the branch circuit indicated at a^7 , through which the input of power to the car operating motor is controlled, a switch a^6 which is operated with the movement of the door engaging device so that when the door engaging device is moved to its extended or operative position, the switch shall be opened and the delivery of power to the motor shall be prevented. A convenient means for controlling the switch may comprise an arm i^2 connected with one of the supporting arms i' of the bar i for normally holding the switch a^6 closed, as shown in Figure 3, but permitting the switch to open when the bar i is moved to move the door engaging device to operative position, as shown in Figure 2. The switch is thus operated with the movement of the normally retracted door engaging device, so that when the latter is in its normally retracted position current may be supplied to the motor to operate the car, and when the door engaging device is moved to its extended or operative position, preliminary to the movement of a door, the switch is opened and current can no longer be supplied to the motor.

It will be understood that various changes in details of construction and arrangement can be made to suit different conditions of use and that, except as pointed out in the claims, the invention is not restricted to the particular construction shown and described herein.

I claim as my invention:

1. In an elevator, the combination of a door, a car, electrical devices through which the movement of the car is controlled, said devices including a switch, a normally retracted device on the car adapted to be moved into extended operative position with respect to the door, pivoted arms, a bar mounted on the arms for moving said device to extended position, and means carried with one of the arms whereby said switch is operated with the movement of said normally retracted device from its retracted position to prevent movement of the car.

2. In an elevator, the combination of a door, a car, electrical devices through which the movement of the car is controlled, said devices including a switch, a traveler, a normally retracted device supported by the traveler and adapted to be moved into extended operative position with respect to the door, pivoted arms, a bar mounted on the arms for operating the traveler, means for moving said device to extended position, and means carried with one of the arms whereby said switch is operated with the movement of said normally retracted device from its retracted position to prevent movement of the car.

This specification signed this 28th day of April, A. D. 1925.

CLAYTON W. OLD.
